UNITED STATES PATENT OFFICE.

GEORGE BESANCON, OF WILKES-BARRE, PENNSYLVANIA.

COTTER-PIN EXTRACTING PLIERS.

Application filed November 4, 1926. Serial No. 146,214.

This invention relates to improvements in pliers, adapted for use in extracting cotter-pins.

An object of the invention resides in providing a pair of pliers having opposed pivotally connected gripping jaws with terminal studs formed at the free ends of the jaws and at one side thereof projecting toward each other in opposed relation for cooperation with the eye of the cotter-pin, while the end portion of the jaws are beveled in a plurality of angularly arranged planes toward the central portion of the body of the jaws so as to provide a plurality of fulcrum faces by which leverage may be obtained on a suitable support for easily removing a cotter-pin from a bolt or the like.

This invention comprehends the provision of a pair of pliers which may be manufactured at a substantially small cost and in which the cotter-pin engages studs which are formed in the jaws with a plurality of beveled faces adjacent said studs which may be formed with a minimum of machine operation so that a tool will be provided which will efficiently perform the operations for which it is designed.

The invention comprehends numerous other objects which reside in the specific construction and relation of the parts as more particularly pointed out in the following detailed description and in the claim directed to the preferred form of the invention, it being understood however, that various changes in the size, shape and arrangement of the parts may be made without departing from the spirit and scope of the invention as herein set forth.

In the drawings forming part of this application:

Fig. 1 is a plan view of the improved pliers formed with the cotter-pin engaging stud.

Fig. 2 is a side view thereof illustrating one manner of using the pliers in extracting a cotter-pin, and

Fig. 3 is an enlarged detail perspective view showing one of the jaw faces to illustrate the detail of how the cotter-pin extracting stud is formed on the end portion thereof.

These cotter-pin extracting pliers include a pair of jaw members 1 and 2 respectively, formed in opposed relation and pivotally connected at one end by the pivot pin 3 in any usual and desired manner of construct-

ing pliers, as well known in the art, and which are formed with handle extensions 4 by which the jaws are moved on the pivot 3. These jaws 1 and 2 are formed in opposed relation and are substantially rectangular in cross-section, being formed however, with cutaway portions 5 in opposed relation and in one side adjacent the pivot to provide the wire cutters 6 operating in 60 to provide the movement of the jaws toward each other or in any well-known manner.

Beyond the recesses 5 these jaws are formed with serrated or corrugated gripping faces 7. Beyond the gripping faces 70 7 the jaws are formed with recessed portions 8 in the opposite faces which increase in depth toward the free ends thereof and terminate with the cotter-pin engaging studs 9. The free ends of these cotter-pin engaging studs terminate in the same plane as the gripping faces 7 of the jaws, and studs 9 on each side of the jaws 1 and 2 projecting toward each other in opposed relation as 75 illustrated in Fig. 1.

These studs 9 are formed so that they are at one side of the longitudinal plane of the pliers shown as in Fig. 2, while the end portions of each of the jaws 1 and 2 are formed with substantially long beveled faces 80 85 10 in place of the usual squared ends. The ends of both jaws 1 and 2 are provided with the beveled faces 11 which extend from the ends of the jaws adjacent the inner opposed faces rearwardly to the outer faces thereof, 90 while the outer side edges at opposite sides of the jaws are provided with the corner bevels 13.

Particular attention is directed to the fact 95 that these beveled faces all converge toward the studs 9. With the studs 9 in cooperating relation in the closed position of the jaws as shown in Figs. 1 and 2, it will be seen that the stud positioned at one side of the jaws as illustrated in Fig. 2 with all 100 of the beveled faces converging toward the studs 9, a construction is provided whereby the ends of the jaws formed with the studs may be readily inserted into restricted pocket recesses in motor vehicle motors and the like, for engagement with eyes of cotter-pins retaining the parts in assembled relation and preventing loss of nuts from bolts, so that the studs 9 may be readily engaged 105 in the eye of the cotter-pin and thru a ratcheting motion of the pliers after engagement with the eye on the faces, 10, 11, or 13, may 110

be rocked in any one of a plurality of directions and these faces engaged with adjacent portions of the motor for a support by which considerable leverage can be obtained for effectively extracting the cotter-pin from an opening in a highly efficient manner.

The provision of the numerous beveled faces converging toward the studs 9 permits the obtaining of a plurality of fulcrum 10 points for the single pair of studs. The angular end portions 10 of the pliers 1 and 2 which terminate and provide beveled ends of a shorter length than the other beveled surfaces on the jaws provide a most effective 15 fulcrum in the extraction of cotter-pins, and for most purposes will be used as the fulcrum face in the extraction of the cotter-pins, while the other beveled faces provide special fulcrums to permit rocking of the 20 tool for removing the cotter-pins where the size and dimensions of the object in which the cotter-pin is mounted limits the position of the pliers when engaged with the pin so that it is necessary for extracting purposes 25 to use other of the beveled faces.

The formation of the studs 9 by recessing the jaws in their opposed faces as indicated at 8 provides a substantially strong structure which will withstand the maximum amount 30 of wear and yet operate in a highly efficient manner, the ends of the studs 9 terminating in the same plane as the face 7, permitting the ordinary use of the pliers for gripping

or wire-cutting purposes in the usual and well-known manner.

It will thus be apparent that a highly novel plier construction has been provided which incorporates the provision of a pair of cotter-pin engaging studs adapted in the co-operation of the jaws for engaging in the eye of the cotter-pin so that a fulcrum movement may be obtained on any one of a plurality of beveled faces on the jaws and considerable leverage obtained by operating the pliers in any one of a plurality of directions 40 for efficiently removing the cotter-pins from a bolt or other means to which it is secured.

Having thus described my invention, what I claim as new is:—

Cotter-pin extracting pliers, comprising a 50 pair of jaw members of substantially rectangular cross-section pivotally connected at one end and formed with handle extensions, the opposite ends of said jaws having opposed gripping faces terminating in recesses 55 formed in the jaws, the extremities of said jaws having studs formed thereon at one side extending in opposed alined relation and terminating substantially in the plane of the gripping faces, the ends, sides, and 60 corners of said jaws being formed with angularly arranged beveled faces converging toward the studs and forming a plurality of fulcrum faces.

In testimony whereof I affix my signature.
GEORGE BESANCON.
